LAKE TORPEDO BOAT COMPANY OF MAINE, OF BRIDGEPORT, CONNECTICUT, A COR-
PORATION OF MAINE.

SUBMARINE BOAT.

1,175,219.

Patented Mar. 14, 1916.

Application filed December 15, 1914. Serial No. 877,410.

To all whom it may concern:

Be it known that I, JOSEPH BARRAJA-FRAUENFELDER, a citizen of the United States, residing at Bridgeport, in the county of Fairfield and State of Connecticut, have invented certain new and useful Improvements in Submarine Boats, of which the following is a specification.

This invention relates to an improvement 10 in submarine or submersible boats and particularly to the construction, arrangement, location and control of the several ballast-tanks designed for holding water ballast for submerging and trimming the boat.

Heretofore, all submarine or submersible boats, so far as I am aware, have their main ballast-tanks located not only centrally but also in the ends of the boat, and their auxiliary tanks wherever practical, depending 20 upon the particular design of the boat, and the location of the machinery, batteries, etc.

The object of my invention is to provide, in a double hull submarine or submersible boat, a peculiar construction, arrangement 25 and location of ballast-tanks, and of the final adjusting tanks, the said tanks being symmetrically grouped about the center of gravity and center of buoyancy of the boat, whereby to dispense with the usual forward 30 and after ballast-tanks, and so that the control of the whole system of tanks may be centralized and operated from a single station.

The invention consists in constructing a 35 submarine or submersible boat with an inner and an outer hull, the latter being arranged throughout practically the entire length of the boat and extended sufficiently far forward and aft of the center of gravity of the 40 boat to provide ballast-tank space between the hull sections of sufficient capacity to hold the necessary quantities of water to adjust the boat into submerging condition, and to compensate for the differences in the 45 specific gravity of waters in which the boat is operating.

The invention further consists in the peculiar and novel arrangement of the valves controlling the inlet of water to the several 50 tanks, and in providing a central control compartment whereby the several valves may be operated from a single station.

The invention further consists in certain 55 peculiar features of construction, combining

and arrangement of parts as will be hereinafter fully described and then claimed.

In the drawings illustrating the invention, in the several figures of which like parts are similarly designated, Figure 1 is a diagrammatic side elevation partly in section of a submarine or submersible boat embodying my invention. Fig. 2 is a horizontal sectional view of the same drawn on a larger scale on the line *a—a* of Fig. 1. Fig. 3 is a diagrammatic transverse section drawn on a larger scale and in the plane of the line *b—b*, Fig. 2. Fig. 4 is a similar view drawn in the plane of the line *c—c*, Fig. 2. Fig. 5 is a similar view drawn in the plane of the line *d—d*, Fig. 2. Fig. 6 is a similar view drawn in the plane of the line *e—e*, Fig. 2.

1 designates the inner or main hull of the boat preferably cylindrical in cross section throughout the intermediate section thereof and having tapering ends of usual construction, and 2 designates the outer hull surrounding the intermediate section of the main hull 1, and having its lower portion substantially semi-circular in cross section with the upper edges of its sides outwardly flaring, and provided with an arched deck 3 which is joined to the sides of the outer hull section air- and water-tight, the outer 85 hull section 2, and the deck 3, thereof, being braced to the main hull by struts (not shown) in the usual manner. The space thus formed between the hull sections is divided transversely by partitions or bulk-heads 4, 5, 6 and 7 which are extended around the lower side of the main hull and up along the sides thereof to the point where the deck 3 is connected to the outer hull 2, and the tops of said transverse partitions or bulk-heads are covered by plates 8 connected air- and water-tight to said partitions or bulk-heads and to the plating of the inner and outer hull sections. The space between the bulk-heads 5 and 6 provides, what I prefer to call, a central or middle main ballast-tank 9 and the spaces between the partitions 4 and 5, and 6 and 7, respectively, provide; what I prefer to call, the forward and after middle main ballast-tanks, 10 and 11, respectively, the latter tanks and the middle 105 main ballast-tank being designed to hold sufficient quantities of sea water to put the

75

100

105

boat into submerging condition. The center of volume of the middle main ballast-tank 9 is arranged to lie substantially in vertical alinement with the center of gravity of the boat and the centers of volume of the forward and after middle main ballast-tanks will lie in longitudinal vertical planes with the center of gravity and spaced an equal distance fore and aft of the center of gravity so that when water is admitted to the center main ballast-tank, and equal quantity of water ballast are admitted to the forward and after main ballast-tanks, the longitudinal and transverse trim of the boat will not be disturbed.

Built upon the main or inner hull and extending through the deck 3 is a navigating-turret 3' which communicates with the central control compartment through a hatch 3'' (Fig. 1) and may be provided with a hatch in its top through which access may be had to the turret from the deck of the boat. In practice the center of volume of the conning-tower will be arranged in substantially vertical alinement with the centers of gravity and buoyancy of the boat.

Water ballast is admitted to the middle main ballast-tank 9 through a manifold 12 having a compartment 13 therein communicating with said ballast-tank 9, and two compartments 14 in open communication with the water of flotation, and which communicate with the compartment 13 through two openings 16 controlled by valves 17 having their stems extended upwardly into a control compartment 18, hereinafter described, and provided with hand wheels.

The compartment 13 communicates with the middle main ballast-tank 9 through an opening 19 controlled by a valve 20 having its stem also extended upwardly into the control compartment 18 and provided with suitable operating devices. The manifold and valves, as well as the manifold and valves (presently described), controlling the admission of water to the forward and after middle main ballast-tanks 10 and 11, form the subject matter of an application Serial No. 877,409 filed by me on even date hereof and as I herein make no claim to the specific construction of the valves and manifolds, I do not deem it necessary to describe or illustrate them in detail as it will be evident that various constructions of valves may be employed for controlling the admission of water ballast to the several tanks. The inner ends of the said ballast-tanks 10 and 11 are provided with ducts 21 and 21' respectively, which are extended into the middle main ballast-tank and terminate below the central control compartment 18 as indicated most clearly in dotted lines in Fig. 2. The ducts 21 and 21' communicate with compartments 22 Fig. 4, formed in manifolds 23 Figs. 2 and 4 arranged in the

middle main ballast-tanks, and like the manifold 12, are formed with compartments 24 which open to the water of flotation and which communicate with the compartment 22 through openings 24', said openings being controlled by valves 25 having their stems extended upwardly into the control compartment 18 and provided with hand operating wheels 26. The communications in the manifolds between the compartments 22 and the ducts 21 and 21', respectively, are controlled by valves 27 also having their stems extended into the control compartment and provided with operating hand wheels 28.

Built within the middle main ballast-tank 80 at the sides of the boat are auxiliary ballast-tanks 30, the centers of volume of contents of which are arranged in transverse alinement with the centers of gravity and buoyancy of the boat. The said tanks 30 are 85 constructed with bottom plates 31 Fig. 3, which are connected air- and water-tight to the plating of the inner and outer hulls, and with sides 31' Fig. 2, which are connected air- and water-tight to the bottom plates 90 31; to the plates of the inner and outer hulls, and to the plates 8, respectively. Water is admitted to the auxiliary tanks through openings formed in the outer hull, controlled by valves 33, the stems of which are extended into the control compartment 18 and provided with hand wheels 34 by which the valves are opened and closed. It may be stated here, that as in all submarine or 95 submersible boats, the auxiliary tanks are designed for holding sufficient quantities of water to compensate for the differences in the specific gravity of fresh and salt water, it being understood, that when the boat is operating in fresh water, the difference in 100 specific gravity of fresh water as compared with salt water, requires the withdrawal of water from the auxiliary tanks in order to put the boat into submerging condition.

Built within the upper ends of the auxiliary tanks are final adjusting tanks 35 of smaller capacity than the auxiliary tanks and designed to receive water ballast for finally adjusting the boat for submergence. The tanks 35 are constructed with bottom plates 36 which are connected air- and water-tight to the inner and outer hull sections, and with end plates 37 also connected air- and water-tight to the plating of the inner and outer hull sections, to the bottom plates 36, and to the plates 8 respectively. Water ballast is admitted to the final adjusting tanks 35 through a common pipe 38 located in the control compartment, having a valve control branch 39 which opens to the water of flotation, or to the middle main ballast-tank as desired, the said tanks being vented through a pipe 40 connected to the tops of the tanks and extended across the top of the inner hull section within the 110 115 120 125 130

superstructure, and having a branch which is extended into the said inner hull and provided with a vent valve 41 operable from within the control compartment. Air is admitted to the final adjusting tanks, to blow the water therefrom, through pipes 42 extending from a suitable source of compressed air supply (not shown) arranged within the boat.

The central control compartment 18 is constructed by transverse partitions or bulk-heads 48 arranged within and connected air and water-tight to the plating of the inner hull, and in practice the bulk-heads will be provided with doorways controlled by doors 45 shown diagrammatically in Fig. 2.

From the foregoing it will be seen that I provide a peculiar, novel and efficient arrangement and construction of water ballast-tanks that is particularly designed for double hull or partial double hull submarine boats, the construction and arrangement thereof being such that all of the ballast-tanks, as well as the final adjusting tanks, may be controlled from a single station within the boat, and which enables me to dispense with the usual forward and after ballast-tanks commonly employed in this class of vessels. It will also be seen that with my construction and arrangement the middle main ballast-tank has its center of volume arranged in vertical alinement with the centers of gravity and buoyancy of the boat when the latter is trimmed to an even keel and that the volumes of the forward and after main ballast-tanks are so disposed with respect to the center of gravity and center of buoyancy that when water ballast is admitted to them the trim of the boat will not be disturbed. Likewise the center of volume of the auxiliary tanks and the center of volume of the final adjusting tanks are also so located with respect to the transverse centers of gravity and buoyancy that when water is admitted to them the buoyancy of the boat will be regulated or adjusted without in the least disturbing either the fore and aft or transverse trim of the boat.

As shown, the tops of the manifolds 12 and 23 are extended through openings formed in the bottom plates of the inner hull, into the control compartments 18, so as to facilitate the cleaning of the valves and the manifolds when the boat is in dry dock.

In practice the middle main ballast tank and the forward and after main ballast tanks will be of a capacity to put the boat into submerging condition and also on an even keel when operating in salt water. In operation, water ballast is first admitted to the middle main ballast-tank, and then simultaneously into the forward and after main ballast-tanks, and finally into the auxiliary

and final adjusting tanks in the usual manner.

By my peculiar arrangement of tanks it will be seen, that when the boat is to be submerged, the sea-valves of the manifolds are first opened to admit water to the upper compartments, therein, so that when the moment arrives to submerge, water may be quickly admitted to the several tanks through the operation of the single valve controlling the inlet to each tank. It may be well to say here, that while I show the valves controlling the admission of water to the forward and after main ballast-tanks as being hand operated, it will be appreciated that two attendants will be required to operate the valves, so that the water may be simultaneously admitted to both of said tanks, however, while not shown in the present application, I do not wish to be understood as limiting myself to any particular form of valve operating gear as it will be evident that by operating said valves through power operative devices they may be simultaneously operated through the manipulation of a device common to all of the said valves. It may be also stated that the sides of the superstructure may be provided with openings to permit the space within the superstructure to automatically fill and drain as the boat is submerged and emerged; however, I do not wish to be limited to this detail as it is evident that the openings in the sides of the superstructure may be controlled by valves to thus render the superstructure watertight for surface navigation.

The central control compartment 18 is provided with a horizontal partition 46 having hatch-ways 47 controlling admission to the lower part thereof, said partition forming a continuation of horizontal partitions 48 arranged in the forward and after ends of the boat.

What I claim is:

1. A submarine or submersible boat, having a middle main ballast-tank the center of volume of which is in substantially vertical alinement with the center of gravity and center of buoyancy of the boat, forward and after main ballast-tanks having their center of volume in substantially the same longitudinal vertical plane with the center of gravity and center of buoyancy of the boat, auxiliary tanks arranged at the sides of the boat, and final adjusting tanks arranged in said auxiliary tanks, the centers of volume of said auxiliary tanks and final adjusting tanks being in the same transverse plane with the center of gravity of the boat, substantially as specified.

2. A submarine or submersible boat, having an inner hull and an outer hull spaced apart, said space containing a middle main ballast-tank the center of volume of which is

- in substantially vertical alinement with the center of gravity and center of buoyancy of the boat, a forward main ballast-tank, an after main ballast-tank, auxiliary ballast-
5 tanks arranged within the middle main ballast tanks, and final adjusting tanks, said tanks being grouped about the center of gravity of the boat, substantially as specified.
- 10 3. A submarine or submersible boat, having an inner hull and an outer hull spaced apart, said space containing a middle main ballast-tank the center of volume of which is in substantially vertical alinement with the center of gravity and center of buoyancy of the boat, a forward main ballast-tank, an after main ballast-tank, auxiliary ballast-
15 tanks arranged within the middle main ballast tanks, and final adjusting tanks, built within the upper portion of the auxiliary tanks, said tanks being grouped about the center of gravity of the boat, substantially as specified, a central control compartment built within the boat, and valves operable
20 from within the said compartment for controlling the admission of water ballast to all of said tanks.
4. A submarine or submersible boat, having a double hull, bulk-heads arranged in the space formed between the hull sections providing a middle main ballast-tank, the center of volume of which is arranged in substantially vertical alinement with the center of gravity and center of buoyancy of the boat, and forward and after main ballast-tanks arranged adjacent to said middle main ballast-tank, the centers of volume of said forward and after main ballast-tanks being in substantially the same longitudinal vertical plane with the center of gravity of the boat, auxiliary ballast-tanks arranged within said middle main ballast-tank at the sides of the boat, and final adjusting tanks built within said auxiliary tanks.
30
5. A submarine or submersible boat, having a double hull, bulk-heads arranged in the space formed between the hull sections providing a middle main ballast-tank, the center of volume of which is arranged in substantially vertical alinement with the center of gravity and center of buoyancy of the boat, forward and after main ballast-
35 tanks arranged adjacent to said middle main ballast-tank, the centers of volume of said forward and after main ballast-tanks being in substantially the same longitudinal vertical plane with the center of gravity of the boat, auxiliary ballast-tanks built within the said central main ballast-tank, at the sides of the boat, final adjusting tanks built within said auxiliary ballast-tanks, a central control compartment built within the inner or main hull of the boat, and independent valves operable from within said central control compartment for controlling the admission of water ballast to the several ballast-tanks and to said final adjusting tanks.
40
6. A submarine or submersible boat, constructed of an inner main hull section and an outer hull section, bulk-heads arranged within the space formed by said hull sections providing a middle main ballast-tank the center of volume of which is in vertical alinement with the center of gravity and center of buoyancy of the boat, a forward main ballast-tank and an after main ballast-
45 tank also built in the space between said hull sections, said forward and after main ballast-tanks each having a duct at its inner end which extends into the said middle main ballast-tank, valves controlling the admission of sea-water to said middle main ballast-tank and to said ducts, a central control compartment built within the inner or main hull of the boat, and means operable from within said control compartment for operating said valves.
50
7. In a submarine or submersible boat, an inner main hull section and an outer hull section, a superstructure arranged above said main hull and connected to said outer hull sections, bulk-heads arranged in the space formed by said hull sections and connected air- and water-tight to said hulls, said bulk-heads providing a middle main ballast-tank the center of volume of which is arranged in substantially vertical alinement with the center of gravity of the boat, and forward and aft main ballast-tanks, the centers of volume of which are arranged in the same longitudinal vertical plane with the center of gravity, substantially as specified, auxiliary ballast-tanks built within the said central main ballast-tank, at the sides of the boat, final adjusting tanks built within said auxiliary ballast-tanks, a central control compartment built within the inner or main hull of the boat, and independent valves operable from within said central control compartment for controlling the admission of water ballast to the several ballast-tanks and to said final adjusting tanks.
55
8. A submarine or submersible boat, constructed with an inner main hull section and an intermediate outer hull section space from said inner hull and partially surrounding the latter, a superstructure built upon said hull sections forming a continuation of said outer hull, partitions or bulk-heads arranged within the space formed by said hull sections providing a main ballast-tank, the center of volume of which is in substantially vertical alinement with the center of gravity of the boat, and forward and after main ballast-tanks having ducts which extend into said central main ballast-tank, auxiliary ballast-tanks built within said middle main ballast-tank at the sides of the boat, final adjusting tanks built within the upper ends of
60

of said auxiliary ballast-tanks, the centers of volume of said auxiliary ballast-tanks and said final adjusting tanks being arranged in the same transverse plane with the center 5 of gravity of the boat, as specified, a central control compartment built within the inner or main hull of the boat, and valves operable from within said control compartment controlling the admission of water-ballast 10 to said middle main ballast-tank; said ducts

and their tanks; said auxiliary ballast-tanks, and said final adjusting tank.

In testimony whereof I have hereunto set my hand this 14th day of December, A. D. 1914.

JOSEPH BARRAJA-FRAUENFELDER.
